[57] CLAIM

The ornamental design for a indicator for game or the like, substantially as shown and described.

DESCRIPTION

FIG. 1 is a front elevational view of a indicator for game or the like showing my new design;

FIG. 2 is a right side elevational view thereof, the side opposite being a mirror image;

FIG. 3 is a bottom plan view thereof;

FIG. 4 is a top plan view thereof; and,

FIG. 5 is a rear elevational view thereof.

Fig. 1.

Fig. 2.

Fig. 3.

Fig. 4.

Fig. 5.
